UNITED STATES PATENT OFFICE.

VERNON W. BALZER AND JOHN MCK. BALLOU, OF LOS ANGELES, CALIFORNIA,
ASSIGNORS TO THOMAS E. HUDSON AND P. G. HUGUS, BOTH OF LOS
ANGELES, CALIFORNIA.

LOCK.

Application filed December 6, 1920. Serial No. 428,758.

To all whom it may concern:

Be it known that we, VERNON W. BALZER and JOHN MCK. BALLOU, citizens of the United States, residing at Los Angeles, in 5 the county of Los Angeles and State of California, have invented a new and useful Lock, of which the following is a specification.

This invention relates to devices for interengaging different members against 10 movement, as in padlocks, door locks, safety locks, vault locks, and other similar devices.

One of the objects of this invention is to hold the bolt in such a lock against turning movement.

15 Another object is to hold a bolt against shifting movement.

Another object is to hold a bolt against a combined shifting and turning movement.

Another object is to provide a bolt which 20 must be shifted in longitudinal direction before it can be turned for unlocking the device.

Another object is to provide engaging 25 members, generally called tumblers, for detaining the bolt in its place or normally locking position.

Another object is to provide tumblers so disposed that the bolt may not be shifted in longitudinal direction until all tumblers are 30 properly set.

Another object is to provide means for preventing the rotating movement of a bolt until a shifting movement has been accomplished, tumblers being provided to hold the 35 bolt against shifting movement until all tumblers are properly set.

Another object is to provide a contact within the lock in coactive relation to the locking members of the device.

40 Another object is to provide a front plate selflocking to the device and so held until the bolt is in releasing position.

Another object is to provide such a lock especially adapted for an automobile lock to 45 be inserted into the wiring system of such automobiles.

Another object is to provide misleading 50 means for misleading in the finding of the correct shifting position through or in relation to the several tumblers.

Other objects will appear from the following description and appended claims as

well as from the accompanying drawing, in which—

Fig. 1 is a longitudinal midsectional view 55 of the device.

Fig. 2 is an end elevation of the flanged end disc seen in the direction of the arrow 2 in Fig. 1.

Fig. 3 is an end elevation of the flanged 60 center or inner disc seen in the direction of the arrow 3 of Fig. 1.

Fig. 4 is an end elevation of the smaller interlocking disc or tumber.

Fig. 5 is a side elevation of the engaging 65 member of the locking bolt in detail.

Fig. 6 is an end elevation of the engaging member of Fig. 5.

Fig. 7 is a cross sectional view through the device on line 7—7 of Fig. 1.

Fig. 8 is a cross sectional view through the device on line 8—8 of Fig. 1.

The whole lock as illustrated in the drawing has been designed with the object in view of making the different parts as far as 75 justifiable of pressed or stamped steel or other similar sheet metal.

It will, however, easily be understood that the parts may just as well be made of other material as long as they are strong enough 80 and otherwise suitable.

The casing 9 is provided with a flange 10 at one end and with a bottom 11 at the other end. The bottom 11 is provided with a bore 12 for the shaft or lock bolt 14, and 85 with a number of perforations 13 according to the number of projecting ends or lips 15 on the inner bottom plate 16. The inner bottom is illustrated in detail in Fig. 3, showing these projecting or extension ends 90 or lips 15, and showing also a peculiarly-shaped bore or perforation comprised of a practically circular portion 17 and the side extension 18. The lips 15 and the corresponding perforations 13 serve the purpose 95 of preventing the inner bottom from turning or moving within the casing 9 when so disposed, as will be more fully described later on. A front plate 19 is disposed over the flanged open end of the casing 9, being provided with a flange 20 and a bore or hole 21. This plate is illustrated in detail in end view in Fig. 2. A sleeve 22 is disposed through the bore 21 for a turning

movement within the front plate 19 and on the bolt or stem 14. The sleeve 22 is provided with a shoulder ring 23 turnably seating against the inside of the front plate 19 and forming a shoulder for the tumblers in the device. The further end 24 of the sleeve 22 forms the seating stud on which the several tumblers are turnably mounted. One of the tumblers, preferably the innermost, that is, the one nearest to the end of the seating stud 24, is secured to the stud by riveting or press-fitting or in other similar manners.

Three tumblers are illustrated in the drawing, but it will easily be understood that any other number of tumblers may be used.

The tumbler 25 is nearest the stud end and shown riveted to the end of the stud 24. The securing of this tumbler can easily be accomplished by roughening or knurling that portion of the seat on the stud 24 on which the tumbler 25 is to seat and then tightly pressing the tumbler on this roughened portion. A slight riveting over as indicated at 28 naturally helps and tends to keep the tumbler in its position on the end of the stud 24.

The outer end 29 of the sleeve 22 is preferably roughened in a similar manner to allow a securing of a dial to this front end.

The one tumbler is naturally secured to the stud 24 so as to allow a free and easy turning and operating of the other tumblers, in this case of the tumblers 26 and 27. The tumblers 26 and 27 then turn and operate easily between the tumbler 25 and the shoulder ring 23 of the sleeve 22, as will easily be understood.

40 The shoulder portion 30 on the stem or bolt 14 is also preferably roughened in a similar manner to securely hold the locking member 31. The member 31 is provided with an extension end 32, bent to project practically parallel to the longitudinal axis of the stem. The front end of the end 32 is provided with a cut-out 33, see Figs. 5 and 6.

The lock is illustrated in the drawing in a position in which the combination of the tumblers has been brought to a point when the locking member can pass through the perforations in the tumblers with the stem in its outermost position in relation to the lock. In the normal locking position, the stem has its position a corresponding distance further in the lock, so that the handle 34 on the front end of the stem practically comes to rest against the front face 35 of 55 outermost point of the lock and the locking member 31 practically comes to rest in or against the bottom 11 of the casing 9. In such locking position, the end 32 of the locking member 31 is withdrawn from the tumblers so that the tumblers can freely turn

without influencing the locking part of the device. The locking member 31, being so secured to the stem in the manner described above, is firmly held and disposed within the peculiarly-shaped hole in the inner bottom plate 16, the practically circular portion 31 of the locking member easily passing through the practically circular portion 17 of the bore in the inner bottom plate, while the end 32 of the locking member partly remains within the portion 18 of the bore or perforation in the inner bottom 16, see Figs. 1 and 3. The end 32 prevents in this manner the stem from turning when in such locking position.

Three tumblers are provided with corresponding perforations 36 to allow the end 32 to pass through the tumblers when the tumblers are set correctly in the combination for unlocking the device, see Fig. 4. Other 85 perforations 37 are preferably provided in the tumblers for misleading in the finding of the combination of the device.

For operating the tumblers, the tumblers 26 and 27 must naturally be operated by the first tumbler 25, and the simplest thing is naturally to have a pin or engaging member in one tumbler for actuating the next tumbler. In the drawing, the pins 38, 39 and 40 serve to transmit the motion from 95 one tumbler to the next one. Corresponding holes or perforations are naturally provided in the flanges of the tumblers. The pins 38, 39 and 40 are shown and illustrated of shouldered form, the smaller portion fitting 100 in the perforations of the flanges of the tumblers while the larger head portions are disposed between the flanges 41 of the tumblers. The pins naturally cannot be dislodged when made in this form, since the 105 head portions of the pins can be made just to fit between two adjoining flanges of the tumblers while the smaller portions can naturally easily be made to fit tightly and securely in the perforations of the flanges 110 of the tumblers, the flanges being indicated at 41.

The pins may, however, be made in form of screws, the threaded portions of the screws to be secured in the perforations of the flanges 41 and the heads or free end projecting out of the flanges for engaging with the screws in the next adjoining tumblers. Such minor modification need, of course, not be illustrated.

A dial 42, is secured to the front end 29 of the sleeve 22 for operating the tumblers and for indicating the positions of the different tumblers. The front end 29 of the sleeve 22, being roughened as described above, naturally allows a securing of the dial by pressing the dial under the press to the end 29 so as to firmly hold against turning and sliding movement.

The stem or bolt 14 with the locking 130

member, as stated and described above, is normally in its innermost position, the locking member 32 disengaged from the tumblers.

5 The pins in the flanges of the tumblers are naturally set and placed in a known combination so as to be adjustable under such a combination, that is, if the tumblers are turned and operated according to such a 10 combination they reach a position in which they allow an opening of a lock. In this case, the locking member 32 can be pushed through the perforations 36 in the tumblers when the tumblers are set in the correct 15 combination.

In the inoperative position, or locking position, when the locking member is in its innermost position, the tumblers can naturally be turned and operated freely and 20 without any trouble.

For setting the tumblers according to a certain combination, the dial 42 is naturally turned back and forth until the combination is reached for letting the locking 25 member pass through the perforations 36, see Fig. 4, in the tumblers.

To prevent a finding of the combination, or at least mislead in the finding of the combination, other perforations 37 are provided in the tumblers, so that the prongs 43 may pass into the perforations 37 while the bottom 44 of the cut-out 33 of the locking member 32 abuts on the remaining cross piece or lip or web 45 in the tumblers, see 30 Figs. 4 and 5. Such engaging of the front end of the locking member, allowing a movement of the bolt 14 to a certain extent outwardly of the device, naturally tends to mislead in the understanding that a correct 35 position of one of the tumblers has been found, but in the search for the right and correct position of the next tumbler the operator will never get through the first tumbler so guarded against a passing of the locking 40 member through such first tumbler, as will easily be understood. Any number of such misleading or guarding perforations can, of course, be provided so that it will be exceedingly hard for a person not acquainted 45 with the particular locking device to find the correct positions of the tumblers for the correct combination.

In the drawing, the innermost end of the stem or bolt is illustrated in the form of 50 contacts so as to prevent an engaging of the contact points of a switch as long as the locking bolt cannot be withdrawn from its locking position in the device. This device is especially suitable as an automobile lock.

60 A bar of copper or similar material, indicated at 46, is embodied in insulating material of bakelite or other similar material, indicated at 47, for engaging with the contact lips 48. A sleeve 49 is suitably secured 65 to each of the double lips or suitably held

to contact with the lips as indicated at 50. The sleeves are provided with flanges 51 so that the screws 52 can be passed through the contact lips 48 and through the flanges 51 on the sleeves, the whole being mounted 70 on a common insulating block 70.

When the locking bolt 14, (and with it, the contact member 46,) is in its innermost position within the device, the contact member is in a position within the cut-outs 54 provided in the front face of the insulating block 53.

Another contact member 55 is provided in the rear end of the insulating block 47 on the stem 14, having a suitable number of engaging lips 56. A corresponding number of contact members 57 are disposed in the insulating block 53.

The heavy electric cable, indicated at 58, for starting the motor of an automobile 85 (that is the starting motor) is in connection with the contact lips 48, naturally preferably soldered in the sleeves 49. The lighter wires, indicated at 59, are then used for ignition purposes.

The whole is inclosed by the outer shell or housing 60. This outer shell is preferably provided with a flange 61 having a corresponding number of screw holes coming into alignment with the screw holes in the flange 95 of the casing 9, as indicated at 62, so that the whole can be secured to the dash-board or any other suitable place of an automobile.

To protect the screws and prevent an undoing of the device without knowing or operating the combination of the device, a front cover plate 63 is provided to cover the whole front except the dial 42. This cover plate 63 is provided with lugs 64 having hook ends 65. The front plate 19, illustrated in detail in Fig. 2, is provided with openings and perforations to allow an insertion of the hook ends 65 through the front plate, the larger portion 66 of these perforations being of such a size that the projections 64 with the hook ends 65 on the cover plate 63 may pass through the front plate 19, while, on a short turning of the cover plate 63, the hook ends 65 come to engage behind the front plate 19.

A pawl 69 is provided on the underside or inner face, having a hook end 70 to engage the projections 64 so that the cover plate 63 cannot be turned unless the locking bolt 14 is withdrawn, accomplished after correctly operating the combination, in which case the front end of the locking member 32 is in a position to actuate the pawl so as to free the lugs or projections 64 so that the cover plate may be turned to bring the hook ends 65 of the lugs to the larger opening or larger portion of the openings in the front plate 19 so that the cover plate may be withdrawn from the engagement with the front plate 19.

The combination lock-switch operates in the following manner; The tumblers are set according to the combination used, so as to bring the perforations 36 in the several tumblers into alignment to allow the locking member 32 to pass through the tumblers. When the locking member 32 is withdrawn from the device to such an extent, the larger portion 31 and the locking member 32 on the bolt 14 are above the inner bottom 16 so that the bolt 14 with the contact member 46 can be turned to engage with the corresponding contact members in the insulating block 53.

As long as the locking member on the stem or bolt 14 is in the position that the locking member is engaged by the inner bottom, the bolt can naturally not be turned and the switch cannot be operated. In such locking position, the tumblers are just turned to some extent that the locking end 32 of the locking member cannot move in the direction towards the front that is through the tumblers.

Any number of perforations can naturally be provided in the flanges of the tumblers, so that the pins 38, 39 and 40 may be disposed in different combinations. One tumbler being only turned, moved, or operated by the engagement of the pin in one tumbler with the pin in the next nearest tumbler, it naturally follows that a changing of the pins to different positions in the different tumblers necessitates different movements of the tumblers before the next adjoining tumblers are moved or dragged along. Such changes can naturally be read from the position of the dial 42 outside of the device.

Having thus described our invention, we claim:

1. In a lock, a tumbler having full-sized and less than full-sized passages parallel to its central axis extending through the whole thickness of the tumbler adapted to allow a co-operating member to pass fully through the full-sized and only to the extent of the thickness of the tumbler through the less than full-sized passages.

2. In a lock, a casing, tumblers turnably disposed in the casing, a locking bolt turnably and shiftably disposed through the center of the tumblers, the tumblers having

full-sized and less than full-sized passages parallel to their central axis, the locking bolt having a locking member projecting sidewise and extending parallel to the longitudinal axis of the bolt, the front termination of the locking member being of a shape to easily pass through the full-sized passages in the tumblers and adapted to pass through the less-than-full-sized passages of the tumblers to the extent of the thickness of one tumbler only, and means to bring the full-sized passages of all tumblers into alignment so that the locking member of the locking bolt can pass to unlock the lock.

3. In a lock, tumblers having full-sized and less than full-sized passages, and a locking bolt having means to pass through the full-sized passages of the tumblers fully while only able to pass through the less than full-sized passages of the tumblers to the distance equal to the thickness of one tumbler.

4. In a lock, a casing, tumblers in the casing having each a central perforation, a dial operatively connected with the tumblers disposed on the outside of the casing, a locking bolt turnably and shiftably disposed through the center of the dial and the tumblers, a locking member projecting radially from the bolt and extending parallel to the axis of the bolt spaced from the bolt, the tumblers having full-sized and less than full-sized passages parallel to the central perforations, the front termination of the locking member being of a shape to easily pass through the full-sized passages when all tumblers are properly aligned by the dial and adapted to pass through the less than full sized passages of the tumblers to the extent of the thickness of one tumbler only when the tumblers are not in proper alignment, and means for holding the bolt against turning movements as long as not all tumblers are properly aligned by the dial.

In testimony that we claim the foregoing as our invention we have signed our names in the presence of two subscribing witnesses.
